UNITED STATES PATENT OFFICE.

JOHN T. KEMPER AND CHARLES W. KEMPER, OF ALAMEDA, CALIFORNIA.

ROPE CLAMP.

Application filed April 20, 1921. Serial No. 462,897.

To all whom it may concern:

Be it known that we, JOHN T. KEMPER and CHARLES W. KEMPER, citizens of the United States, residing at Alameda, in the 5 county of Alameda and State of California, have invented new and useful Improvements in Rope Clamps, of which the following is a specification.

This invention relates to a rope or cable 10 clamp, and especially to that type of clamp where the cables lie parallel and in contact with each other, and where a clamping action is obtained by one or more wedges.

One of the objects of the present invention is to generally improve and simplify cable clamps of the character described, and especially to provide a substantial easily applied clamp whereby cable ends may be effectively secured and locked against longitudinal movement with relation to each 20 other and the clamp.

Another object of the invention is to provide a cable clamp employing one or more wedges adapted to directly engage the 25 cables, and which are so proportioned and of such length that bruising, cutting or other damage to the cables is positively prevented; further to provide a clamp which is self-locking and automatically increases its 30 clamping action in proportion to the pull or strain exerted.

Another object of the invention is to provide means for securing the wedges against removal when the clamp is not in use; also 35 to provide means for securing the wedges against releasing or retrograde movement when in a clamping position; further to maintain the wedges in an elevated position at all times where they will not interfere 40 with the free insertion or removal of the cable ends.

Another object of the invention is to provide a cable clamp which is so constructed that the cables may be inserted through the 45 sides of the clamp, thus providing a clamp which is universally applicable.

Further objects will hereinafter appear.

The invention consists of the parts and the construction, combination and arrangement of parts as hereinafter more fully described and claimed, having reference to the accompanying drawings, in which:

Figure 1 is a central vertical longitudinal section through the clamp showing the 55 cables and the wedges in position.

Fig. 2 is an end view of the clamp.

Fig. 3 is a side elevation of the clamp showing a slot formed in the side thereof, through which the cables may be inserted.

Referring more particularly to the drawings, A indicates in general the clamp forming the subject matter of the present invention. The clamp consists of a pair of side walls 2 and 3, which are tied together by a rounded top section 4 and a rounded bottom section 5. Extending longitudinally through the clamp is a central passage 6, through which a pair of cable ends such as indicated at 7 and 8 are adapted to be passed. Also formed within the clamp or between the side and end walls thereof are a pair of wedge receiving chambers 9 and 10. These chambers communicate with the central passage 6 and the wedges 11 and 12 insertable therein are adapted to directly engage the 75 opposite sides of the cables 7 and 8 as shown in Fig. 1. The outer rounded ends of the wedge receiving chambers are inclined as shown at 13. One face of each wedge is also inclined as shown, and a downward movement is thus imparted to each wedge when inserted, said downward movement being employed for the purpose of gripping the cables and securing the same against longitudinal movement with relation to the 85 clamp proper. The wedge receiving chambers have a width slightly greater than the central passage 6. A pair of ledges 14 is in this manner formed, which prevents the wedges from dropping down into the central 90 cable receiving passage. This is of importance, as the wedges might otherwise interfere with the insertion of the cables.

For the purpose of securing the wedges against loss or accidental removal when the 95 clamp is not in use, and for the purpose of securing the wedge against retrograde movement when in clamping position, we employ a pair of bolts such as indicated at 15. These bolts pass through perforated lugs 16 formed at each end of the clamp and through openings 17 formed at the inner ends of the respective wedge receiving chambers. Each wedge has a central opening formed therein which is threaded to receive 105 the bolts and turning movement imparted to the bolts will therefore advance or retract the wedges with relation to their respective chambers and the cables 7 and 8.

In actual operation when employing a 110 clamp such as shown in Figs. 1 and 2, it is only necessary to turn the bolts in such a

direction as to force the wedges outwardly with relation to their chambers. This permits free insertion of the cable ends 7 and 8 through either end of the clamp as both ends are open. When the cable is inserted it is necessary to draw up the wedges. This is usually accomplished by striking the projecting ends of the respective wedges with a hammer and driving them tightly into place, or it may be accomplished by applying a wrench to the head of each bolt and turning the same in a direction which will pull the wedge inwardly with relation to their chambers. If the wedges are driven in by hammer action it is also preferable to apply a wrench to tighten up the bolts after the wedges have been driven into place, as the bolts will then secure the wedges against retrograde movement and may in fact serve the function of further tightening the wedges. In the present instance we employ wedges of considerable length and as the wedges are wider than the diameter of the cables 7 and 8, see Fig. 2, it is obvious that a large bearing surface is formed between each wedge and the respective cables. This surface is preferably rounded as shown at 18 to conform with the contour of the cable and it may be corrugated or roughened if desired, to form a better bite or grip. In any instance it can be seen that such a large gripping area is presented that a secure hold is formed and danger of bruising or cutting the cables is entirely obviated. In fact a number of experiments have proven that when a cable spliced or secured as here shown is subjected to a severe pull or a pull sufficient to part the cable it has been found in every instance that the cables never part within the clamp, but always exterior of the same, thus proving that the wedges in no instance damage or weaken the cables.

In the type of clamp employed in Figs. 1 and 2 it is necessary to thread the cables through one end or another of the clamp when applying the same. This is more or less difficult under certain conditions, and particularly when handling fairly heavy cables. To obviate this difficulty we have provided a form of clamp such as shown in Fig. 3. This clamp is identical to the clamp shown in Figs. 1 and 2, with the exception that one of the side walls is slotted from end to end as indicated at 20 to form a longitudinal opening through which the cables may be inserted through the side of the clamp. This materially facilitates the application of the clamp under certain conditions.

While the clamp illustrated in both Figs. 1 and 3 employs two wedges and bolts, it is obvious that a clamp might be constructed employing a single wedge and bolt, and further it should be obvious that various changes in design, proportion, etc., might be resorted to within the scope of the appended

claims without departing from the spirit of the invention.

Having thus described our invention, what we claim and desire to secure by Letters Patent, is:

1. A rope clamp comprising a housing having a passageway formed therein and extending therethrough for the reception of a pair of parallel contacting cables, a wedge receiving chamber also formed in the housing and communicating with the cable passage, a wedge insertable therein and directly engageable with one of the cables, the large end of the wedge extending exterior of the chamber so that it may be struck by a hammer and driven into the chamber, means for securing the wedge against end-wise removal, and a track-way within the wedge chamber limiting movement of the wedge toward the cable. 75 80 85

2. A cable clamp comprising interspaced side sections and integral top and bottom sections, a central passage formed therein and extending therethrough, a pair of open-ended, longitudinally extending tapering passages formed between the top and bottom sections and in communication with a central passage, the apexes of said tapering passages extending toward each other, a wedge member insertable in each tapering passage and directly engageable with cables extending through the cable passage, guideways formed in the sides of the clamp to prevent the wedges from entering the cable passage, and a bolt having threaded engagement with each wedge to limit longitudinal movement thereof with relation to the tapering passages. 90 95 100 105

3. A cable clamp comprising a housing having a cable channel formed therein, said channel extending from end to end of the casing and being centrally disposed with relation thereto, a wedge chamber formed at each end of the housing and at opposite sides thereof, each wedge chamber communicating with the cable passage and each wedge chamber being open at its opposite end, a lug formed on each end of the housing and at opposite sides thereof, said lugs being perforated and being in alignment with the open ended wedge receiving chambers, a wedge insertable in each chamber, a threaded passageway formed in each wedge, and a bolt for each wedge, said bolts being insertable through the perforated lugs and adapted to be received by the respective threaded passages in the wedges. 110 115 120 125

4. A cable clamp comprising a housing having a cable channel formed therein, said channel extending from end to end of the casing and being centrally disposed with relation thereto, a wedge chamber formed at each end of the housing and at opposite sides thereof, each wedge chamber communicating with the cable passage and each wedge cham-

ber being open at its opposite end, a lug formed on each end of the housing and at opposite sides thereof, said lugs being perforated and being in alignment with the 5 open ended wedge receiving chambers, a wedge insertible in each chamber, a threaded passageway formed in each wedge, and a bolt for each wedge, said bolts being insertible through the perforated lugs and adapted 10 to be received by the respective threaded passages in the wedges, said wedge receiving chambers and the wedges received thereby being wider than the cable passage to form guide ledges for the wedges which will limit 15 the movement of the wedges toward the cables.

5. A cable clamp comprising a housing having a cable channel formed therein, said channel extending from end to end of the 20 casing and being centrally disposed with relation thereto, a wedge chamber formed at each end of the housing and at opposite sides thereof, each wedge chamber communicating

with the cable passage and each wedge chamber being open at its opposite end, a wedge 25 insertible in each chamber, and a pair of bolts carried by the clamp, one in each side thereof and connected with the respective wedges to exert a pull thereon.

6. A rope clamp comprising a housing 30 having a passage-way formed therein and extending therethrough for the reception of a pair of parallel contacting cables, a wedge receiving chamber also formed in the housing and communicating with the cable passage, a wedge insertible therein and directly engageable with one of the cables, the large 35 end of the wedge extending exterior of the chamber so that it may be struck by a hammer and driven into the chamber, and a bolt 40 carried by the housing and having threaded engagement with the wedge to exert a pull thereon.
